UNITED STATES PATENT OFFICE.

ALBERT HIORTH, OF ASKER, NEAR CHRISTIANIA, NORWAY, ASSIGNOR TO A/S
HIORTH'S ELEKTRISKE INDUKTIONSOVN, OF BERGEN, NORWAY.

ELECTRIC INDUCTION FURNACE.

1,410,304.

Specification of Letters Patent. Patented Mar. 21, 1922.

Application filed February 9, 1921. Serial No. 443,548.

To all whom it may concern:

Be it known that I, ALBERT HIORTH, a subject of the King of Norway, residing at Asker, near Christiania, Norway, have invented certain new and useful Improvements in Electric Induction Furnaces for Smelting Metals and the like; and I do hereby declare the following to be a full, clear, and exact description of the invention, such 10 as will enable others skilled in the art to which it appertains to make and use the same, reference being had to the accompanying drawings, and to letters or figures of reference marked thereon, which form a part 15 of this specification.

The present invention relates to induction furnaces for smelting metals and the like, and the invention consists therein that the smelting takes place in a closed chamber, 20 which is connected with a compressor or evacuator for the purpose of performing the smelting under vacuum or under any desired pressure and in any kind of atmospheres.

For this purpose the annular vessel serving to take up the charge is enclosed in an air-tight shell or jacket preferably consisting of thin sheet metal or the like and connected with a pipe conduit by means of 25 which the vessel may be put in communication with a suction or pressure device.

On the drawing a form of the invention is illustrated.

1 is the magnetic core, 2 the primary winding and 3 the smelting channel (the secondary) in an ordinary induction furnace. The smelting channel 3 is as usual provided with a refractory lining 4, and the lining according to the invention is provided with an air-tight jacket 5 of sheet metal. To this jacket is connected a suction 35 or pressure pipe 6 by means of which the jacket may be evacuated or put under pressure, or may be filled with different gases.

Claim:

An induction furnace comprising an annular charge containing vessel having an annular smelting channel formed therein, an air tight jacket closely conforming to and enclosing the vessel, a primary winding and a magnetic core outside of the jacket, and 40 means to evacuate the space within the jacket.

In testimony that I claim the foregoing as my invention, I have signed my name in presence of two subscribing witnesses.

ALBERT HIORTH.

Witnesses:

GEORGE G. FULLER,
JOHN L. SULLIVAN.
